R. D. SMITH

PULL SOCKET CUT-OUT ARRANGEMENT

Filed Nov. 3, 1920

Patented July 13, 1926.

UNITED STATES PATENT OFFICE.

RAYMOND D. SMITH, OF SCARSDALE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

PULL-SOCKET CUT-OUT ARRANGEMENT.

Application filed November 3, 1920. Serial No. 421,555.

My invention relates to electric switches that incorporate automatic cut-out mechanism and has specific reference to pull-operated switches for lamp sockets, particularly of the general, well-known type described by me in my copending application, Serial No. 421,556, filed November 3, 1920.

A primary object of the present invention is to provide in the now standardized and approved form of double-break, socket-pull switch mechanism referred to above, a novel arrangement of the usual switch contact parts and of automatic switch-governing mechanism co-operating therewith, for effecting, automatically, a delayed circuit-breaking action of the switch a substantial interval of time after the pull chain has been actuated in the usual manner for extinguishing the light.

Specifically, my present invention contemplates, as a means for accomplishing the above object, the introduction into said standardized form of switch mechanism of a novelly arranged thermo-motive device that may be electrically energized through a switch-controlled auxiliary circuit; and further contemplates, for co-operating with the action of said motive device, an advantageous re-arrangement of certain fixed inclined contact plates, characterizing the type of switch mechanism concerned.

In the particular embodiments of the invention illustrated herein, I employ, as a means for governing the energization of the thermo-motive device, a partial movement of the usual, S-shaped, rotatable, current-switching member from its normal circuit-making position to a position intermediate its usual positions for respectively making and breaking the main circuit through the lamp. For this purpose I preferably introduce an auxiliary stationary contact positioned to be engaged by said member for diverting current therefrom to the operating circuit for the thermo-motive device when said member is moved to its said intermediate position. Specifically, I find it convenient to mount such auxiliary contact on a common insulating support with one of the original, fixed, and inclined contact-plates that, as usual, is connected in the main circuit,

I may, however, so arrange the various electrical connections that the operating circuit for the thermo-dynamic device shall be energized through such auxiliary contact by being connected in shunt to the lamp (or other switch governed load) or in series therewith. The embodiments herewith illustrated show the latter arrangement, which possesses the advantage that by adding the resistance of the lamp to that of the electrical unit governing the thermo-motive device, there is eliminated any necessity of employing an auxiliary rheostat for lowering the line voltage at the terminals of the said unit in cases where the latter (because of limitations of structure or of space) possesses, in itself, too little ohmic resistance to permit of its being subjected directly to the full line voltage when energized.

These and other advantageous features of the present improvement will be hereinafter described in detail and are clearly illustrated in the accompanying sheet of drawings wherein:—

Fig. 1 is a view of my improved pull-socket switch looking downwardly on the current switching parts, the pull-operated actuator being indicated in broken lines, and the rotatable contact wiper shown in normal, circuit-making position.

Fig. 2 is a front elevation of the complete pull-socket switch showing the casing in section and the detent-controlling thermo-stat and certain other parts partially broken away for clearness.

Fig. 3 is a view similar to Fig. 1, showing the contact wiper in advanced circuit-closing position and arranged for automatic circuit-breaking action.

Fig. 4 is an enlarged fragmentary view looking in the direction of arrow 4 in Fig. 3, showing more clearly the relation of contact parts.

Fig. 5 is a diagram of electrical connections.

Fig. 6 is a fragmentary plan view showing a modification wherein a thermostatically driven pawl device is substituted for the restraining detent shown in Figs. 1 to 5 inclusive, the wiper being shown in advanced circuit-closing position and arranged for automatic circuit breaking action.

Fig. 7 shows the position of these modified parts in normal circuit making position, the pawl, however, being shown in a position which it occupies when the thermostat is heated.

Fig. 8 is a fragmentary view in front elevation showing the pawl device of Fig. 6; with the thermostat omitted.

Throughout the several views of the drawing identical parts are designated by the same reference numeral.

The switch is of the familiar ratchet-step-contact type, embodying between the insulating base 10 and insulating top plate 11, a central, vertical pivot-stud 12 about which rotates the contact-bridging wiper 22, the latter, in the form shown, being substantially S-shaped and provided with downwardly sloping and diametrically opposite, conductive, wiper arms 23, 23.

These arms wipe over circularly arranged, inclined steps 17, 18, 19 and 20, formed on the base 10, and terminating consecutively in abrupt insulating shoulders 21, which prevent retrogressive rotation of the wiper between steps.

An insulating actuator segment 25, operated by the pull-chain 32, is pivoted to swing, on the stud 12, and to drive the wiper arms 23 over the said steps in increments of progressive rotation through engagement of registering teeth 33 and shoulders 34 on the actuator and wiper respectively,—the coiled spring 30, performing the double function of rotatively returning the actuator after each stroke on the pull-chain and of pressing the actuator axially against the wiper 22, thus maintaining the latter in wiping engagement with the said incline steps. Brackets 35 and 43 form stops to limit the swing of the actuator at each end of its stroke.

The incline step 17 carries a contact plate 37, electrically connected to one leading-in wire 60; diametrically opposite, incline steps 18, 20 are blank, and in my present improvement, the remaining step 19 carries two separate and insulated contact plates 38 and 39, electrically connected as will later be described, the latter occupying the upper part and the former the lower part of the step incline surface this particular mechanical relation however being variable with respect to the requirements of differently designed electrical relations for the main and auxiliary circuits, hereinbefore mentioned as possible alternatives in practicing my invention. Contact plates 37 and 39, at diametrically opposite points relative to the center of the switch, are each bent at their terminal portion near the top of the step shoulders 21, to form an angle having an upwardly disposed apex, and a terminal 40 sloping downwardly from said apex. Thus the wiper arms 23 when rotatively advanced

over the apexes of the terminal portions of contact plates 37, 39, will, without further manually caused movement, tend to slide simultaneously from off the two sloping contact plate terminals 40 leaving the same with a quick snap due to the axial action of spring 30, and thus producing automatically a quick and double break of the circuit through said wiper and said contacts.

A detent lever 41, is pivoted on the stationary stud 42 mounted on the base 10 in a position to intercept one of the two wiper spurs 46, 46, when the ends of the wiper arms are resting on the sloping plate terminals 40, as shown in Fig. 3, and is thus operative normally to check the tension-caused rotative advance of the wiper before the arms 23 are discharged automatically from the said terminals. The detent lever is thus operatively positioned by the curved bimetallic, flexing thermostat 49, which at its free end 48 engages with the insulated detent lever projection 47 and at its opposite end is rigidly mounted on the insulated bracket 55 which carries the bell-mouth guide 31. The thermostatic lamina of greater expansibility is on the inner side of the thermostat.

A fine resistance wire 50 is wound on the thermostat and insulated therefrom. This wire, when electrically energized by the passing of current therethrough, acts to heat the thermostat and cause a straightening flexure therein, which flexure retracts the detent lever 41 from the path of spur 46 in the manner indicated in Fig. 3. One end 29 of the wire 50 is connected to the center-supported contact 38, that transmits current to the center-terminal, contact-tongue 66 for the incandescent lamp 62; the other end 28, of the wire 50, is attached to the insulated contact 39 which is secured to the base 10 by a screw 59. An outer casing 52 and metallic cap 51, interlocked by screws 77, are provided as usual, together with a bell-mouth guide 31 for the pull-chain 32.

The operation is as follows: In the circuit-making position of parts shown in Fig. 1, the current passes from the leading-in wire 60 through the binding-post bracket 35 to the contact plate 37, thence through the wiper 22 to the contact plate 38, central screw 65, terminal tongue 66, filament (not shown) of the incandescent lamp 62, threaded lamp receptacle 53, screw 67, binding-post bracket 36, to the other lead wire 70.

A full stroke upon the pull-chain will advance the actuator 25, and wiper 22, substantially 90°, and the wiper arms 23 into the position shown in Figs. 3, 4 and 5, in which position the wiper is arrested by the detent lever 41 as heretofore explained, the circuit paths here remaining as before except that current cannot now flow from the wiper 22 directly to the contact 38, but

must go from said wiper through the contact 39 and the resistance wire 50 and thence to contact 38, which path for the current establishes the said resistance wire in series with the lamp and so energizes the former to heat the thermostat.

When sufficiently heated the thermostat operates to retract the detent lever 41 as described, thus releasing the wiper 22 after 10 a short time interval and permitting axial tension in spring 30 automatically to effect circuit-breaking discharge of the wiper arms 23, 23 from the contact plates 37, 39.

Another stroke upon the chain will again 15 advance the actuator and wiper approximately 90° and into a position similar to that shown in Fig. 1, thus lighting the lamp in the usual way, and independently of the thermostatic detent.

20 In this connection it should be noted that the diametrically opposite shoulders 21, of the blank steps 18 and 20, should be so spaced in the circle that the ends of wiper arms 23, will have passed said shoulders 25 when the actuator 25 is stopped by insulated bracket 43. Since the degree of travel of the wiper 22 as driven by a full stroke of the actuator is substantially the same in both 30 circuit-making and circuit-breaking action, and since it is required that at the end of such actuator stroke, the arms 23 shall clear steps 18 and 20 for circuit-making action, but shall not clear the plate-terminal 40 in circuit-breaking action, it follows that 35 terminals 40 must each be spaced further from the preceding blank step shoulders respectively, than from the succeeding shoulders, or specifically (referring now to only one side of the switch) there must be more 40 degrees of space between terminal 40 of plate 39, and shoulder 21 of step 18, than between said terminal and the shoulder 21 of step 20. The only positional requirement of the shoulders of steps 17 and 19, however, 45 is that they shall not extend in advance of the plate terminals 40. In the present disclosure, merely as an incident of illustration, the said shoulders are shown substantially in alignment with said terminals. The steps 50 17 and 19 obviously may possess any formation advantageous to the support of their respective contact plates.

An important feature of structural detail 55 is that the separated contact plates 38 and 39 are placed not merely end to end but are formed with registering notches and extensions to overlap each other in the same surface plane and in spaced relation thus insuring that one or both of said plates will 60 at all times be contacted by the wiper arms when said arms traverse or occupy the steps that carry these two plates.

The arrangement is also preferably such 65 that the actuator segment 25 is stopped by the insulated bracket 43, or other suitable

means just after the ends of the wiper arms 23 have passed over the apexes of the angular contact plates 37 and 39 and before contact occurs between the spur 46 and the detent lever 41, the wiper being then advanced 70 automatically to effect such contact by the discharging action of spring 30.

A modified arrangement of automatic wiper-governing device is shown in Figs. 6 to 8 inclusive. Here the terminal portions 75 of contact plates 37 and 39, as shown in Fig. 8, are formed to have no, or at least so little, downward slope that the axial tension exerted by spring 30 is not in itself sufficient to cause the automatic circuit-breaking discharge of arms 23, 23 in the manner described in Figs. 1 to 5. In this modification therefore, the detent lever 41 is replaced by a trigger frame 71 composed of two arms 72 fast to a common hub 73 pivoted to swing on the stud 42. These arms carry a vertical pivot pin 74 on which is pivoted a trigger finger 75, normally positioned relative to the trigger frame 71 as shown in full lines in Figs. 6 and 7 by the 80 spring 76, and permitted to yield to the broken-line position indicated in Fig. 6 against the tension in said spring. In the operation of this arrangement, the bracket 43 stops the actuator 25 as usual when the 85 end of the wiper arms are positioned as in Fig. 6. As before stated, these arms are not in this modification capable of automatic circuit-breaking discharge by the spring 30, when in this position, but when said position 90 is reached spur 46 has advanced to its position shown in Fig. 6 in advance of the trigger finger 75 the latter yielding to permit the passing of the former,—and in the manner before described the thermostat is then 95 heated to cause its outbending which swings the trigger frame 71 clockwise in Fig. 6 about the stud 42, and by engagement of the finger 75 with spur 46 drives the wiper 100 rotatively until the ends of arms 23 clear 105 the contact plate terminals 40 whereupon the spring 30 acts to break the circuit in the usual manner. It should be noted that here the spring 30 is relieved of what, in the 110 forms shown in Figs. 1 to 5, inclusive, is, 115 in effect, the imposition thereupon of an additional function, namely, that of causing rotative advance of the wiper 22 (by the exertion of axial pressure thereon) in a direction that is opposite to the rotative 120 direction in which said spring exerts its torsional force for returning the actuator 25 to the beginning of its stroke.

Preferably, in the modified arrangement just described, a second spur 45 is formed 125 on each of the arms 23 and so positioned as to engage with a square shoulder 63 on the hub of the trigger finger for preventing rotative movement of the wiper to its position 130 as shown in Fig. 6 unless the thermostat is

normally cool. This feature is desirable to assure that spur 46 shall always properly pass the trigger finger to be later engaged and driven thereby as described, which, due to the geometrical arrangement, would not be the case were the thermostat not permitted to become normally cool before subsequent advance of the wiper to its position as shown in Fig. 6. If the lamp, after being extinguished, is immediately turned on again, the thermostat must have time to cool before the lamp can be again extinguished, since the finger 75 and the spur 63 assume the position indicated in Fig. 7 so long as the thermostat remains hot.

As before stated, the circuit connections herein described are merely illustrative of an electrical arrangement which enables the thermostatic detent to be governed by the switch controlled current through the simple and efficient structural arrangement of main and auxiliary contact plates as herein described. It will be understood however that such arrangement is adaptable and advantageous to many other circuit arrangements, such, for instance as that employed in the switch described in my other application hereinbefore referred to wherein the thermostat winding is energized by being connected in shunt to the lamp, or directly across the supply line.

Relative to the particular structural type of lamp socket that I have herein chosen as illustrating a useful application of my present improvement in switch mechanism (namely the fixture type of socket adapted for electrical connection with leading-in current-supply wires by means of binding-post screws) it should be noted that although the aggregate socket and switch structure is so compactly arranged that substantially no increase in size of such a structure is necessitated, yet the binding-post screws for the leading-in wires are sufficiently spaced and otherwise removed from interference by any of the new parts, that the addition of such new parts has introduced no disadvantageous features of fragility or complexity to require unusual care or attention on the part of the unskilled workman in assembling and installing my improved pull socket. It will further be observed that the binding-post screws (which are important elements in fixture sockets) as employed in a pull socket embodying my invention, are of the same size and in the same location as customarily constructed in non-automatic socket switches. My improved switch mechanism, however, may readily be incorporated in any of the various other structural types of pull sockets, such, for instance, as the "adapter form," that is designed as a temporary attachment to be interchangeably interposed between any standard electric socket and its usual incandescent lamp.

The feature illustrated in Figs. 1 to 5 inclusive; wherein the abrupt incline of contact terminal 40 tends to discharge contact arms 23 into a circuit breaking position except when restrained by detent 41, is not claimed in this application, but is the subject matter of claims in my co-pending application, Serial No. 421,556, filed November 3, 1920.

Having thus described a preferred and specific embodiment of my improved switch mechanism, I make the following claims as descriptive of my invention, but without intention to limit the scope of such invention to the precise form and arrangement of details herein disclosed.

1. Controlling mechanism designed to be operated by successive manual actuations, and having means automatically to delay for a limited interval of time the operative response of said apparatus to one of the said manual actuations, said means embodying, in combination; a rotatively driven ratchet member; a pawl-carrying actuator therefor mounted to oscillate and arranged by successive manually-caused forward strokes to impel said member intermittently and positively in the same direction; ratchet seats arranged consecutively in the path of said member for normally positioning the same; means to cause a stroke of said actuator for normally positioning said member on one of said ratchet seats, and further arranged to limit the subsequent stroke of said actuator before said member has been impelled thereby to its normal position on the next succeeding ratchet seat; and a slow-acting motive device operatively related to said member as manually caused by the said stop-limited, subsequent actuator stroke, thereby automatically to impel said member to its normal position on the said succeeding ratchet seat after a substantial interval of time.

2. In an electric switch having a one-way rotatable current-switching member, an oscillatory actuator therefor arranged by successive strokes in the same direction to advance said member progressively step-by-step to make and break a main circuit, and means to cause a stroke of said actuator for establishing said member in a normal circuit-making position, in combination; a circuit-connected fixed contact mounted and co-operatively positioned relative to said member to remain conductively engaged by said member, after advance of the latter from its said normal circuit-making position as caused by a stroke of said actuator subsequent to the circuit-making stroke thereof whereby said circuit is retained temporarily closed; and a slow-acting motive device operatively related to said member and connected to be rendered active by the said subsequent actuator stroke thereby automatical-

ly to move said member away from said contact to break the said circuit.

3. In an electric switch having a one-way rotatable current-switching member, an oscillatory actuator therefor arranged by successive strokes in the same direction to advance said member progressively step-by-step to make and break a main circuit, and means to cause a stroke of said actuator for establishing said member in a normal circuit-making position, in combination; a circuit-connected fixed contact mounted and co-operatively positioned relative to said member to remain conductively engaged by said member, after advance of the latter from its said normal circuit-making position as caused by a stroke of said actuator subsequent to the circuit making stroke thereof, whereby the said circuit is retained temporarily closed; and a slow-acting motive device operatively related to said member and connected to be rendered active through the said further advance of said member, thereby automatically to impel said member to a further advanced position to break the said circuit.
4. In a pull socket having pawl-and-ratchet switch-operating mechanism, including a current-switching member mounted for step-by-step rotative advance to control a circuit, and a pull-operated spring-retumed actuator arranged by one stroke thereof to advance said member to a normal circuit-making position and by a subsequent stroke thereof to advance said member further and toward a normal circuit-breaking position thereof, in combination; means normally operative to arrest the said subsequent actuator stroke before said member reaches said normal circuit-breaking position; and a slow-acting motive device connected to be set in operation by said subsequent oscillator stroke, and arranged thereupon automatically to impel said member to its said circuit-breaking position, after a substantial interval of time.
5. In a pull socket having pawl-and-ratchet switch operating mechanism, including a current-switching member mounted for step-by-step rotative advance to control a circuit, and a pull-operated spring-retumed oscillator arranged by one stroke thereof to advance said member to a normal circuit-making position and by a subsequent stroke thereof to advance said member further and toward a normal circuit-breaking position thereof, in combination; means normally operative to arrest the said subsequent actuator stroke before said member reaches its said normal circuit-breaking position and a thermodynamic device operatively related to said subsequent oscillator stroke, thereby to be rendered slowly active to impel said member to its said circuit-breaking position, after a substantial interval of the time.

6. In an electric switch with circuit con-

nnections for a switch-governed load and having a rotatable pivoted contact-wiping member tensioned for sliding engagement with a fixed leaf circuit-contact mounted to cause a quick snap-break movement of said member transverse the said contact when the former passes the latter, to cut out the load, in combination; electro-thermally actuated instrumentalities having a governing circuit and arranged automatically to impel said member past said leaf contact; the said contact being electrically connected to govern an operating circuit for said instrumentalities, and positioned to be engaged by said member for energizing said circuit when the member is substantially advanced relative to its normal load-energizing position; together with connections to retain the switch governed load in circuit during the period of energization of said instrumentalities.

7. In a pull socket switch embodying a rotative, load-controlling current-transmitting member arranged to be driven intermittently in the said direction through limited intervals of circuit-controlling travel and in wiping engagement with spaced, inclined contact plates, said member being tensioned against said plates, whereby quick discharge of said member from the respective terminals of consecutive plates is caused upon rotation of the former past the latter, in combination; auxiliary current-switching means arranged to be operated by movement of said member through only a part of one of its said increments of travel; and an automatic motive device electrically controlled by said current-switching means, and adapted when rendered operative to impel said member automatically to the end of its said increment of travel for quick circuit-breaking discharge from one of the said contact plate terminals.

8. A pull socket switch having a movable contact member mounted as a pawl-driven ratchet wheel, and co-operating inclined fixed contact leaves mounted in the path of said member and on insulating supports, arranged to co-act with said member as stationary click-steps for normally positioning the same; in which one of said insulating supports carries a plurality of separate contact leaves connected respectively in different switch-controlled circuits, whereby movement of said member between its normal successive positions, as determined by the said insulating supports, operates sequentially to control the energization of said different circuits.

9. A pull socket switch having a movable contact member mounted as a pawl-driven ratchet wheel and co-operating inclined stationary contact leaves mounted in the path of said member and on insulating supports, arranged to co-act with said member as sta-

- tionary click-steps for normally positioning the same; in which one of said insulating supports carries a main circuit-connected contact leaf and an auxiliary circuit contact 5 leaf insulated therefrom, said main and auxiliary contact leaves being co-operatively positioned so that said member engages operatively with only one of said leaves in a designed rotative position relative to said 10 support but engages operatively with the other of said leaves upon substantial advance movement of said member from its last mentioned position.
10. A pull-socket switch embodying in combination, contact insulating and supporting tables; a stationary main circuit contact plate carried on one of said tables; two separate contact plates carried on another of said tables and positioned thereon 15 in spaced relation, one of said separate plates being connected in the main circuit; a current-switching rotor pivoted to wipe over said plates in its travel, said separate plates being positioned respectively to be 20 electrically connected to said first plate in variable relation in different positions of said rotor; an electro-thermal motive device having electrical connection to the other of said separate plates whereby said device is energized only in a designed position of said 25 rotor; and automatic instrumentalities governed by said electrical device and arranged to cause delayed main-circuit-breaking movement of said rotor when said device is 30 energized.
11. In an electric switch, a movable current switching member, means to advance said member toward a normal circuit breaking position, with means to arrest the same 35 before said member reaches said normal circuit breaking position, and a slow acting motor device connected to be set in operation simultaneously with said movement and arranged automatically to impel said member to its circuit breaking position after a 40 substantial interval of time.
12. An electric socket switch having a lamp circuit, a contact controlling member, means manually to move the latter, a device 45 to complete the movement of said member, said member being placed in operative relation to said device by the manual movement thereof, and electrically responsive means to move said device and cause extinguishment 50 of the lamp after a substantial period of time following the manual movement of said member.
13. An incandescent lamp switch having a delayed action control for retarding the 55 lamp extinguishing action, and including an impelling device to complete the lamp extinguishment, and a thermo-electrically controlled member to move said impelling device.
- 60 14. A lamp switch having a movable contact member, a delayed action control for retarding lamp extinguishment, including a thermo-electric device, and a normally inactive impeller for the control member rendered active by said thermo-electric device. 70
15. An electric switch having a movable contact controlling member, means to initiate a circuit breaking movement thereof, a normally inactive impelling device to complete the movement of said member, and a thermo-electrically controlled device to render said impelling device active after the lapse of a substantial period of time following the initiation of said circuit breaking movement. 75
16. An electric switch having a manually actuated contact controlling member with means for initiating a circuit breaking movement thereof, a normally inactive impelling device operatively related to said contact controlling member, and electrically responsive means to render said member active to exert a moving force against the contact controlling member to complete the circuit breaking movement only after the lapse of a substantial interval of time. 80
17. An electric switch having means to initiate a circuit changing movement, and a normally inactive impelling device with means for rendering the same active after the lapse of a substantial time automatically to complete the circuit changing movement. 85
18. An electric switch having a contact member, means to initiate a circuit changing movement of said member, and a delayed action motive device automatically to impel said member thereby to complete its circuit changing movement after the lapse of a substantial time. 90
19. A pull socket switch having a rotary contact member, an oscillatory actuator, one or more stationary inclined contact leaves mounted in the path of said member, insulating supports for the latter arranged to co-act with said member as stationary click steps for normally positioning the same, means to delay lamp extinguishment for a substantial period of time following a lamp extinguishing movement of the actuator, and an auxiliary control contact for said delay means also arranged on one of said insulating supports to be engaged by said rotary contact member. 105
20. A pull socket switch having a rotary contact member, an oscillatory actuator, one or more stationary inclined contact leaves mounted in the path of said member, insulating supports for the latter arranged to co-act with said member as stationary click steps for normally positioning the same, means to delay lamp extinguishment for a substantial period of time following a lamp extinguishing movement of the actuator, and an auxiliary control contact for said delay means upon one of said insulat- 110
- 115
- 120
- 125
- 130

ing supports and positioned adjacent to but insulated from one of said main contacts, said auxiliary and main contacts being positioned to be simultaneously engaged by said contact member in one position of the latter and said main contact to be engaged alone in another position of said member.

21. A pull socket switch having a rotary contact member, an oscillatory actuator, one or more stationary inclined contact leaves mounted in the path of said member, insulating supports for the latter arranged to co-act with said member as stationary click steps for normally positioning the same, means to delay lamp extinguishment for a substantial period of time following a lamp extinguishing movement of the actuator, and an auxiliary control contact for said delay means upon one of said insulating supports and positioned adjacent to but insulated from one of said main contacts, said rotary contact member being related to said main and auxiliary contacts to engage said main contact alone in one position, both of said contacts in a succeeding position and said auxiliary contact alone in a further position.

22. A pull socket switch having a rotary contact member, an oscillatory actuator, one or more stationary and main contact leaves mounted in the path of said member, means to delay the lamp extinguishing movement for a substantial period of time following the lamp extinguishing movement of the actuator, and an auxiliary leaf contact for controlling said delay means insulated from but in juxtaposition to one of said main contacts, whereby both of said main and auxiliary contacts are engaged by the contact member in one position of the latter.

23. In an electric lamp switch, the combination with a one-way rotary contact controlling member, an oscillatory actuator, one or more stationary main contacts mounted in the path of said member, the latter being adapted to be moved by said actuator to disengage from said main contact or contacts and extinguish the lamp, means to delay the lamp extinguishing movement of said member for a substantial interval after the lamp extinguishing movement of said actuator, said means including a control device engaging said contact controlling member, and an auxiliary control contact for said delay means adapted also to be engaged by said rotary contact member.

24. In an electric lamp switch, the combination with a one-way rotary contact controlling member, of an oscillatory actuator, one or more stationary main contacts mounted in the path of said member, said member being adapted to be moved by said actuator to disengage from said main con-

tact or contacts and extinguish the lamp, delay means to delay the lamp extinguishing movement of said member for a substantial interval after the lamp extinguishing movement of said actuator, and an auxiliary wiper contact for controlling said delay means also within the path of said rotary contact member and engaged by the latter when said actuator is moved to extinguish the lamp.

25. In an electric switch, the combination with a movable contact controlling member, an actuator, one or more stationary contacts mounted in the path of said member, the latter being adapted to be moved to disengage from said main contact or contacts and extinguish the lamp, means to delay the lamp extinguishing movement of said member for a substantial interval, and an auxiliary wiper contact for controlling said delay means within the path of said contact controlling member.

26. In an electric lamp switch, the combination with a movable contact controlling member, a main contact mounted in the path of said member, said member being adapted to be moved to engage with and disengage from said main contact in lighting and extinguishing the lamp, means to stop the lamp extinguishing movement of said member and allow the completion of the same only after a substantial interval of time has elapsed, and an auxiliary wiper contact for controlling said stop means within the path of said rotary contact member and adapted to be engaged in one position of the latter simultaneously with said main contact.

27. In an electric lamp switch, the combination with a movable contact controlling member, a main contact mounted in the path of said member, said member being adapted to be moved to engage with and disengage from said main contact in lighting and extinguishing the lamp, means to stop the lamp extinguishing movement of said member and allow the completion of the same only after a substantial interval of time has elapsed, and an auxiliary contact for controlling said stop means also within the path of said movable contact controlling member, the latter being adapted to engage the main contact alone to light the lamp and in a succeeding position to engage both main and auxiliary contacts, and in its aforesaid stop position to engage the auxiliary contact alone.

28. In a pull actuated switch, in combination, inclined contact supporting steps, a contact rotor pressed into engagement with said steps, and two contacts mounted in spaced and insulated relation on a common one of said steps, thereby to be traversed by said rotor in its sliding movement over said

step to energize in predetermined sequence two circuits terminating respectively at each of said contacts.

29. An electric light switch embodying in combination, with a slow acting motive device furnishing power to slowly move the switch contacts, an actuator for positioning the said switch contacts to close the light

circuit and connections whereby subsequent movement of said actuator sets in operation 10 said motive means.

Signed at Boston, in the county of Suffolk and Commonwealth of Massachusetts, this 25th day of October, 1920.

RAYMOND D. SMITH.
